UNITED STATES PATENT OFFICE.

CARL SCRABIC, OF URBANA, OHIO.

TONE-ARM CONSTRUCTION.

Application filed March 28, 1921. Serial No. 456,046.

To all whom it may concern:

Be it known that CARL SCRABIC, a citizen of the United States, residing at Urbana, in the county of Champaign and 5 State of Ohio, has invented certain new and useful Improvements in Tone-Arm Constructions, of which the following is a specification.

This invention relates broadly to improvements in sound reproducing machines, and has specific reference to an improved tone arm construction therefor, the primary object of the invention being to provide a tone arm which will include articulately 10 related sections capable of supporting a reproducer or sound box in such manner that the latter may have its position easily and conveniently altered so as to be capable of reproducing both the lateral and hill-and-dale type of records, and to permit 15 this object to be accomplished in such manner that direct metallic contact between the joints of the tone arm sections will be precluded.

Another object of the invention resides 20 in providing a universal joint connection between the inner and outer sections of the tone arm, the said joint allowing for vertical movement of the outer end of the tone 25 arm in order that the reproducer carried thereby may be lifted out of engagement or dropped into reproducing relationship 30 with the grooves of a record, and the said joint being further formed to include a vertical pivot which will be operative to 35 allow for lateral movement of the reproducer when the latter is reproducing a record, a structure therefore being provided which will serve to maintain the stylus of 40 the sound box in a proper position at all times within record grooves, and to enable the instrument to automatically adapt and accommodate itself to irregularities in the 45 curve characteristics of said grooves.

A further object of the invention resides 50 in providing the inner end of the tone arm with an improved pivotal bearing, the latter including a stationarily mounted casing in which the inner end of the tone arm is rotatably received, the said casing and tone 55 arm being provided with spaced sets of horizontally situated anti-friction bearings, which serve to enable the tone arm to swing horizontally, freely and without friction and also to provide an efficient construction

for supporting the overhanging outwardly extending portions of the tone arm.

Other objects of the invention reside 60 in a tone arm wherein the above features are present, and also of the structural features which serve to produce a construction capable of being economically and easily manufactured, to provide an efficient conduit for transmitting sound vibrations from a reproducer to an amplifier construction 65 in such manner that the passage of the sound vibration through the tone arm will be free and unobstructed by outside influences, and to form the various joints of the tone arm so that direct contact between 70 relatively movable metallic members will not result in setting up vibration or extraneous metallic chatter.

The invention accordingly consists, in the 75 novel features of construction, combinations of elements and arrangements of parts, hereinafter to be fully described and pointed out in the appended claim.

In the accompanying drawing:

Figure 1 is a vertical transverse sectional 80 view taken through the tone arm comprising the present invention,

Figure 2 is a transverse vertical sectional view taken along the line 2—2 of Figure 1,

Figure 3 is a similar view taken on the 85 plane indicated by the line 3—3 of Figure 1,

Figure 4 is a detail view of the spring employed in the outer joint of said arm, and

Figure 5 is a horizontal sectional view 90 taken along the line 5—5 of Figure 1.

Referring more particularly to the details of the invention, and to the specific form thereof disclosed in the accompanying drawing, the numeral 1 designates my improved tone arm in its entirety. This tone 95 arm is formed from a plurality of continuous, substantially telescopic sections, preferably formed from seamless tubes, which are adapted to be assembled in a manner to be hereinafter specifically set forth. The tone arm as a whole is pivotally mounted as at 2 in connection with the cabinet 3 of a talking machine, in order that the outer end of said arm may swing on the usual horizontal plane across the playing surface of a record 4, the latter being adapted to be rotatably and removably carried by the usual revolving turn table 5, which may be driven by means of an ordinary motor shaft 6. It will be understood 105 110

that the reproducer or sound box 7, carried by the outer end of a tone arm 1, will carry the usual stylus construction 8, which may be arranged for cooperation with the grooves 5 of the record 4 in a manner customary to apparatus of this character.

The tone arm 1 includes at its inner end a vertically pivoted elbow section 9, which carries at its lower end a sleeve 10 of rubber, leather or any other non-vibratory material. Arranged to be rigidly secured in connection with the section 9, and to surround the sleeve 10, is a metallic sleeve 11 which, in this instance, includes vertically spaced horizontally extending collars 12, the latter being adapted to provide seats for hardened steel rings 13, which are adapted to receive a plurality of anti-friction devices 14, in this instance in the form of 20 ball bearings.

The cabinet 3 is provided with a metallic casing 15, which is arranged to concentrically surround the lower end of the section 9, the said casing being provided with an internal chamber 16, in which the sleeve 11 is rotatably received. The lower end of the casing projects through an opening 17 formed in the cabinet 3, and in this instance the casing is formed with an integral 30 outstanding collar 18, which is adapted to rest upon the upper surface of the cabinet 3 and to be secured stationarily to the latter by means of fastening screws or their equivalents 19. The bottom of the casing is 35 formed with an inwardly directed annular flange 20, which provides a seat for a steel ring 21, the latter being arranged for cooperation with the lowermost of the rings 13 and in combination with the latter provides a raceway 22 for the reception of the 40 lower set of ball bearings 14. It will be observed that the flange 20 is annularly recessed to receive a gasket ring 23, which serves to prevent direct metallic contact between the lower end of the section 9 and the flange 20, and also to prevent outside air currents from entering the sound conduit by way of the joints provided between the section 9 and the casing 15.

The upper end of the casing is threaded as at 24 to receive a closure member 25, which also carries a steel ring 26 for cooperation with the ball bearings provided upon the uppermost of the rings 13, and to thus produce a raceway 27 which will be positioned in a plane above the raceway 22. It will be apparent that when the closure member is removed the structure constituting the pivotal mounting for the tone arm may be readily positioned within the chamber 16, and then by the application of the closure member, the parts will be rotatably maintained within the casing and prevented from moving vertically in an undue manner therein. By threading the closure

member upon the casing, it will be manifest that the proper degree of pressure may be brought to bear upon the bearings 14 so as to insure their proper positioning within the raceways 22 and 27 and to thus provide for a freely rotatable tone arm. It will be observed that by reason of this pivotal construction, the said tone arm will be capable of oscillating freely and easily, and therefore but a minimum of friction will exist between the stylus of the tone arm and the grooves of the record during the movement of the tone arm across the record, a feature which results in considerably diminishing the scratching or grating noises which are ordinarily apparent in record reproduction. Also, by spacing the raceways 22 and 27 in the manner set forth, it will be apparent that the weight of the outer overhanging end of the tone arm may be readily taken care of in such manner that all binding in the pivotal mounting will be eliminated. If desired, a vertical web 28 may be provided between the collars 12, which will be capable of contacting with stationary stops 29, in order that the swinging movements of the outer end of the tone arm will be limited to a prescribed art.

The upper end of the sleeve 10 terminates in an outwardly directed horizontally extending portion 30, which is adapted to receive the enlarged end 31 of a rigid tubular section 32, the end 31 being secured within the upper end of the section 9 in any suitable manner, such as by a drawn or a 100 soldered connection so that the sections 9 and 32 will constitute a rigid unitary part of the tone arm.

The outer end of the section 32 has formed thereon a rigidly carried cup shaped member 33 which forms an essential part of a universal joint construction 34, which is utilized in articulately connecting the outer and inner sections of the tone arm. To this end, the member 33 includes vertically aligned and extending trunnions 35, which receive a ring 36 and serve to confine the latter within the cup 33 so that the ring will be permitted to swing on the vertical pivots afforded by said trunnions. It will be observed that the outer face of the ring is of curved formation in order that the same will be permitted to swing about the trunnions without interference on the part of the inner wall of the cup member.

The ring 36 is, in turn, provided with horizontally situated pivot pins 37, which have their pointed ends arranged to be positioned within aligned depressions provided upon opposite sides of a substantially spherical head 38, which is rigidly carried upon the inner end of a pivoted tube section 39. Preferably, a rubber or other similar sleeve 40 is positioned between the head 38 and the end of the tube section 39, in order that

direct contact between metallic parts will be eliminated. Similarly, an enlarged gasket 41 is seated vertically within one end of the cup member 33, and is arranged between the outer end of the section 32, its cup member 33 and the ring 36 and spherical head 38. This gasket prevents direct contact between relatively movable metallic parts but serves more essentially in sealing the sound passage between the sections 32 and 39, so that outside atmospheric disturbances will not be permitted to enter the conduit. By reason of the universal joint, it will be apparent that the sound box 7 carried upon the outer end of the tone arm may be dropped upon or lifted from a record by swinging the outer end of the tone arm about the pivotal axis defined by the pins 37, the spherical formation of the head 38 permitting of such relative movement on the part of the section 39 with respect to the ring 36. In this instance, the head 38 or its equivalent is adapted to be provided with a stop shoulder 42, which is capable of engaging with one edge of the ring 36 to limit downward movement on the part of the sound box. Then, by reason of the provision of the vertical trunnions 35 the sound box will be capable of having an independent horizontal swinging movement with respect to the main swinging movement of the sections 9 and 32 of the tone arm. This supplemental swinging movement is provided in order that the outer end of the tone arm and the reproducer may be adapted to follow irregularities in the record construction. However, by use of the compound pivotal joint 34, the sound box will be permitted to move laterally and vertically so that the stylus 8 thereof may be properly maintained within the grooves of a record, that is, the stylus or needle will have its lower extremity at all times centrally positioned within a record groove and to thus avoid undue frictional contact between the stylus and the walls of a groove. While the outer end of the tone arm will be permitted to swing a slight distance about the vertical pivots 35, yet by the provision of the gasket 41, undue swinging movement will be precluded and the tube sections 32 and 39 normally maintained in longitudinal alignment.

The outer end of the tube section 39 is flexibly connected with the extreme outer section 43 of the tone arm by means of a novel and improved joint 44, the function of which joint being to enable the sound box 7 to be adjusted so as to be capable of reproducing both lateral and hill-and-dale cut records. To this end, the outer portion of the tubular section 39 is downwardly and angularly inclined as at 45 with respect to the longitudinally extending portions of said section. The inclined portion

45 terminates in a relatively enlarged bell-shaped mouth 46 in which is rotatably received the inner and upwardly inclined angularly extending end 47 of the section 43, the axis of the portions 45 and 47 being coincident. The mouth 46 includes a gasket 48, which is seated between adjacent walls of the portions 45 and 47 and acts to prevent direct contact of the movable metallic parts, and yet permits of free rotation of the end 47 relative to the section 43. To control the extent of this rotation, the end 47 is provided with diametrically disposed rigidly projecting studs 49, which are arranged so that their outer ends will be received within an arcuate slot 50 provided in the wall of the inclined portion 45. The slot 50 is of substantially 90° in length, in order that when the sound box is being adjusted from one operative position to another, the contacting of the stud 49 with the end walls of the slot 50 will serve to insure a proper positioning of the sound box. It will be understood that the said sound box is adapted to be carried by the outer end of the section 43, and that when in the position shown in Figure 1, the same will be adapted for use in reproducing lateral cut records, however, by swinging the section 43, the outer end of the latter may be caused to assume a position capable of permitting the sound box to reproduce hill-and-dale records. To maintain the sections 39 and 43 in their positions of relative adjustment, the angular end 47 is provided with a collar 51, which is adapted to be received within the mouth 46, and arranged to be positioned between the inner wall of the collar and an annular shoulder 52 is a spring washer 53, the said washer normally serving or tending to force the section 43 away from the outer end of the section 39, this movement, however, being counteracted by the studs 49. It will be observed that the ends of the slot 50 are formed with notches 54, which are so located that when the sound box has been properly adjusted the spring 53 will serve to force the studs 49 into one or the other of said notches and to thus lock the sections 39 and 43 together. It will be understood that the reproducer 7 may be secured in any approved manner to the outer end of the section 43.

In view of the foregoing description, taken in conjunction with the accompanying drawing, it will be apparent that the present invention provides a tone arm wherein is to be found many improved features of improved construction. In this respect, it will be observed that by the provision of the compound joint 34 the reproducer, connected with the tone arm, is capable of being properly maintained and centered in conjunction with the groove of

a record and to automatically accommodate itself to the irregularities, more or less slight and noticeable, which are present in all records. Secondly, an improved joint 5 is provided in the outer sections of the arm for enabling the sound box to be properly adjusted for various types of records, and to be positively maintained in such adjustment 10 in an efficient, convenient and effective manner. Thirdly, a tone arm is provided including articulately related sections which are so formed and united that relatively movable metallic parts will be maintained out of physical contact, and to thus reduce 15 or eliminate undue metallic vibration in the tone arm. Fourth, the joint constructions are such that the interior of the tone arm or the sound conduit therethrough, is sealed so that extraneous atmospheric disturbances will be prevented from entering 20 the sound conduit and disturbing the sound vibrations properly set up therein, and finally, an improved construction is provided for effecting the pivotal support of 25 the tone arm as a whole, in order that the latter may oscillate freely and without un-

due friction across the playing surface of a record, and to compensate for the relatively heavy offset or overhanging outer end of the tone arm, so that the weight of such end will not interfere with the pivotal movement of the tone arm about its main vertical axis.

What is claimed is:

In a tone arm, communicating inner and outer sections, a compound pivotal connection between said sections consisting of a ring arranged to be received within the outer end of the inner section, vertical trunnions between said ring and the outer end 35 of the inner section, a curved enlargement provided upon the inner end of the outer section, horizontal trunnions uniting said enlargement with said ring, and a gasket formed from a compressible material and 40 situated between said ring and the outer end of said inner section, said gasket serving to maintain said ring in a normal position and to seal the conduit provided by 45 said sections.

In testimony whereof I affix my signature.

CARL SCRABIC.
